GRAIN SEPARATOR

Marcus A. Erickson and Johannes Groseth,
Minneapolis, Minn.

Application January 18, 1932, Serial No. 587,186

13 Claims. (Cl. 209—96)

This invention relates to new and useful improvements in grain separators, generally, and more particularly to the type of separator employing a cylindrical separating member having its inner surface provided with suitable indentations and through which member the material to be separated and cleaned is fed.

An object of the invention is to provide a grain separator comprising a cylinder having its interior surface provided with suitable indentations, and provided at one end with means for delivering thereto the material to be separated, and means being provided within the cylinder adapted to receive certain particles of the material in elective quantities, carried upwardly by said indentations, and discharge them from the cylinder into suitable receiving means.

A further object is to provide a grain separator comprising an indented cylinder into one end of which the material to be separated is fed, and trough-like members being mounted within the cylinder adapted to receive different materials carried upwardly by the indentations in the wall thereof, said trough-like members being mounted for independent adjustment, and the adjustability of said members providing means whereby the degree of separation of one material from another may be controlled.

A further object is to provide a grain separator comprising a cylinder having its walls provided with suitable indentations adapted to receive the different materials to be separated, and a plurality of trough-like members being mounted within the cylinder and having their receiving edges adapted to be disposed at different elevations, whereby one of said members may be arranged to receive certain of said materials, while another may be positioned to receive different materials.

A further object is to provide a machine of the class described comprising two indented cylinders, one mounted over the other, and a suitable feed means being provided at one end of the upper cylinder adapted to feed the material to be separated into said cylinder, and trough-like members being provided within said upper cylinder adapted to receive certain materials carried upwardly by the indentations in the walls of said cylinder, said trough-like members being oppositely disposed whereby material delivered into one of said members will be discharged from the upper cylinder through the receiving end thereof and delivered into the receiving end of the lower cylinder, and the material delivered into the other of said trough-like members, which

may be clean grain, being discharged from the opposite end of the upper cylinder into a suitable receiving means, and the lower cylinder having one end portion provided with medium sized indentations, while the opposite end thereof is provided with relatively smaller indentations and trough-like members also being provided within the lower cylinder and inclined in the same general direction; the member at the receiving end of the cylinder being adapted to receive the material carried upwardly by the relatively larger indentations at that end of the cylinder and delivering it into the second section of the same cylinder for the purpose of regrading and reseparating; and the relatively larger material which is not carried upwardly by the indentations in the first section of the cylinder being discharged from the grader as cleaned material through suitable openings provided in the wall of the cylinder. The object of thus releasing from the first section of the cylinder, the material already thoroughly cleaned and graded, is first; to maintain that particular grade separate from other grades discharged from the machine, and second; to establish a concentrated mixture which is delivered into the second section of the cylinder for the final clean up of the small seeds from the small and broken grains. This final clean up or separation is effected by the relatively smaller indentations provided at that end of the cylinder; the material carried upwardly by these smaller indentations being delivered into the trough-like member provided therein from whence it is discharged from the end of the cylinder into a suitable receiving means, the tailings being discharged separately from the same end of the cylinder into another receiving means.

Other objects of the invention reside in the means provided in connection with one of the trough-like members for preventing elective portions of the material carried upwardly by the indentations in the walls of one of the cylinders from being delivered into said member whereby said material is returned to the cylinder for further separation; in the means provided for independently adjusting the trough-like members within the cylinder to effect the proper separation of the materials being separated; in the means provided for tilting the cylinders with respect to the ground level so as to control the flow of material therethrough; in the unique manner in which the material to be separated is fed through the machine whereby the various materials contained in the mixture separated from one another

and delivered into their respective receiving means; in the means provided for controlling the feeding of the material into the machine; in the means provided for causing some of the material delivered into the machine to be returned for a second separation; in the means provided for removing the dust and lighter foreign particles from the material as it is fed into the cylinder to be separated; and in the general construction of the machine, as a whole, whereby a separator is provided which is capable of thoroughly separating from one another, all of the various materials contained in the mass, and at the same time dividing the main product such as wheat, into three different grades, thoroughly cleaned and graded as to length, and delivering them into their respective receiving means, and in the operating mechanism of the machine whereby the latter may be operated with a minimum of power.

Other objects of the invention will appear from the following description and accompanying drawings and will be pointed out in the annexed claims.

In the accompanying drawings there has been disclosed a structure designed to carry out the various objects of the invention, but it is to be understood that the invention is not confined to the exact features shown as various changes may be made within the scope of the claims which follow.

In the drawings:

Figure 1 is a cross sectional view on the line 1—1 of Figure 2, showing a machine comprising two cylinders arranged one over the other, and also showing the means provided therein for conducting the separated materials to their respective receiving means;

Figure 2 is a front elevation of the machine showing the means for adjusting the trough-like members within the cylinders;

Figure 3 is a rear elevation of the machine showing the driving means for the cylinders;

Figure 4 is a cross-sectional view on the line 4—4 of Figure 1;

Figure 5 is a sectional plan view on the line 5—5 of Figure 4 showing the means provided for vertically adjusting one end of the machine;

Figure 6 is a detail sectional view on the line 6—6 of Figure 1 showing the receiving end of the upper cylinder;

Figure 7 is a detail sectional view on the line 7—7 of Figure 2, showing the trough-like member provided at the front end of the upper cylinder, some of the parts being broken away;

Figure 8 is a sectional plan view on the line 8—8 of Figure 2;

Figure 9 is a diagrammatic view showing in full and dotted lines, different positions of the trough shown in Figure 7, and also showing the means provided in connection with said trough for returning certain of the coarser material for re-cleaning;

Figure 10 is a view similar to Figure 9, showing the parts in different positions;

Figure 11 is an enlarged detail view showing how certain of the material is delivered into the trough by the combined actions of gravity and centrifugal force; and

Figure 12 is a detail sectional view through the receiving end of the upper cylinder showing how the material to be separated is constantly fed onto an empty or bare surface of the cylinder.

The novel grain separator featured in this invention is shown comprising a suitable frame composed of uprights 2—2 and 3—3 secured to-

gether at one end of the frame by suitable cross rails or members 4—4. The members 3—3 at the opposite end of the frame are shown secured together by suitable cross members 5 and 6. Suitable angle iron rails 7 secure together the uprights 2 and 3 at each side of the machine, as best shown in Figures 1 and 8.

In the preferred form of the invention, a pair of cylinders 8 and 9 are rotatably mounted in the frame. The upper cylinder 8 has the inner surface of its receiving end provided with suitable indentations, and the rear half of this same cylinder is preferably provided with slightly smaller indentations than those provided in the front half of the cylinder. These indentations are adapted to carry portions of the material to be separated, such as all small seeds and other foreign material which is smaller than the grain being cleaned, and also elective portions of the main mixture, upwardly and deliver them into a receiving means which will subsequently be described. The rear half of the lower cylinder 9 is provided with indentations of a smaller size than those provided in the rear half of the upper cylinder 8, and the front half of the lower cylinder 9 is provided with indentations of a smaller size than those provided at the opposite end of this same cylinder. Hereinafter, the end of this machine at the right in Figure 1, will be referred to as the front end, while the opposite end thereof will be referred to as the rear end.

The front end of the upper cylinder 8 has an annular member 11 secured therein which has a raised portion 12 adapted to ride or travel upon a pair of suitable rollers or wheels 13 and 14, shown suitably mounted upon a plate 15 secured to the uprights 3—3. The opposite end of the cylinder 8 has an annular member or head 16, fitted thereto, as shown in Figure 1. This annular member 16 is provided with a circular plate 17 spaced therefrom by suitable spacers 18. The circular plate 17 is provided at its inner central portion with an annular flange 19, providing an opening 21 through which the material to be separated is fed into the end of the cylinder. The opening 21 is so arranged with respect to the direction of rotation of the cylinder, that the unseparated material being fed to the machine is delivered directly onto an empty or bare surface of the cylinder wall whereby it is immediately subjected to the action of the indentation 10, as will be clearly understood by reference to Figure 14. By thus delivering the unseparated grain onto an unoccupied surface of the cylinder, the initial separation is greatly facilitated.

A hub 22 is secured to the annular flange 19 by suitable arms 23, as shown in Figure 6, and this hub is secured to one end of a shouldered stub shaft 24, having a reduced end portion rotatably mounted in a bearing 26 provided in a small housing 27, shown secured to the cross member 4 of the machine frame by suitable bolts 28, as shown in Figure 3. A suitable collar 29 is secured to the exterior end portion of the reduced end portion of the stub shaft 24, and cooperates with the shoulder provided at the inner end of said reduced end portion to prevent longitudinal movement of the stub shaft 24 in the bearing 26. An agitator 50 is secured to the stub shaft 24 to prevent the material from becoming congested in the bottom of the housing 27.

A shaft 31 extends through the cylinder 8 and has one end supported in the hub 22 of the circular plate 17 and has its opposite end rotatably supported in a sleeve 32, mounted in an aper-

ture provided in the plate 15 at the front end of the machine. A member 33 is secured to the rear end portion of the shaft 31 adjacent to the bearing 22, and has an annular flange fitting 5 within the head 16 of the cylinder 8, as best shown in Figure 1. The central portion of the member 33 is offset and is adapted to fit over the inner portion of the flange 19 of the circular plate 17, and cooperates with the opening defined 10 by said annular flange to provide a means for directing the material to be separated into the receiving end of the cylinder 8. The member 33 is provided with an inwardly extending flange 35 preferably V-shaped as shown in Figure 6, 15 adapted to provide a seat for a trough-like member 36, one end of which is secured to the flange 35 and the intermediate portion of which is supported by the shaft 31, the bottom of said trough-like member being apertured to receive the shaft 20 as shown in Figure 1.

An arm 37 is secured to the outer end of the shaft 31 at the front end of the machine, as best shown in Figures 2 and 8, and is shown provided with a slot 38 adapted to receive one end 25 of a link 39 which is pivotally supported upon the plate 15, as shown in Figure 2. A suitable thumb screw 41 is received in threaded engagement with the arm 37 and provides means for clampingly engaging the link 39 to secure it to the arm 37. By means of the above described parts, the shaft 31 and therefore the trough-like member 36 may be rotatively adjusted within the cylinder 8 and locked in the desired adjusted position.

A discharge spout 42 is provided at the front 35 end of the machine and projects through a suitable opening 43 provided in the plate 15, as shown in Figure 2. The spout 42 is supported upon a plate 44 provided with a hub 45 in which the sleeve 32 is secured by means of a suitable set 40 screw 46. The sleeve 32 provides a support for the front end of the shaft 31. The plate portion 44 of the spout 42 is preferably shaped as shown in dotted lines in Figure 2 so as to substantially close the opening 43 provided in the plate 15, 45 regardless of the position of the spout 42. The plate portion 44 of the spout 42 has an inwardly extending flange 47 preferably V-shaped in form and providing a support for one end of a trough-like member 48, the bottom of which is inclined 50 as shown in Figure 1 and extends upwardly to a point substantially mid-way of the length of the cylinder 8. The bottom of the member 48 is apertured to receive the shaft 31.

An adjusting arm 49 is secured to the outer end 55 of the sleeve 32, as shown in Figure 1, and extends laterally therefrom, as shown in Figure 2 and has a slot 51 therein adapted to receive a link 52 similar to the link 39, but somewhat longer. A suitable screw 53 is received in threaded engagement with the arm 49 and provides means for securing the arm to the link 52, the latter being pivotally mounted upon the plate 15, as shown in Figure 2. Thus, it will be noted that by means of the arm 49, the trough-like member 48 is adapted for adjustment with the cylinder 8 independently of the trough-like member 36 provided at the rear of the machine. The trough-like member 48 at the front of the machine is provided at one side with a small trough 54 inclined in the opposite direction from that of the member 48. This trough 54 is adapted to receive a portion of the grain carried upwardly by the indentations in the cylinder 8 and convey such material rearwardly towards the center of the cyl-

inder 8, whereby said material will be subjected to a second separation.

A similar trough 55 is provided at the opposite side of the member 48 and has its upper end positioned beneath an opening 56 provided in the wall of the member 48, as best shown in Figure 7. A plurality of members 57 are pivotally mounted upon the shaft 31 and each has an end portion adapted to engage the wall of the member 48 at the receiving side thereof, as shown in Figure 10 10 15 9. The relatively shorter end portions 58 of the members 57 are adapted to direct the material delivered onto the upper portions of the members 57 through the opening 56, in the wall of the member 48, and into the trough 55, whereby 15 such material will be returned to the intermediate portion of the cylinder 8, and subjected to a further separation, as will be understood by reference to Figure 7.

The coarsest material such as oats, barley, 20 sticks, and pieces of straw, which might be intermixed with the mass of material fed to the machine, will not be carried upwardly by the indentations in the cylinder 8, but will be discharged from the front end of the cylinder 25 through a spout 59 provided at the lower end of the plate 15, as shown in Figures 1 and 4. The upper portion of the spout 59 is provided with inclined walls 61 and 62, extending upwardly as shown in Figure 2, and the wall 62 projecting 30 above the opposite wall 61, as indicated at B, so as to catch any material which may be carried upwardly by the rotary motion of the cylinder 8, whereby such material will be delivered into the spout 59 from whence it will flow by gravity into 35 a suitable receiving means, not shown.

The means provided for feeding the material to be separated into the cylinder 8 is best shown in Figure 1, and comprises a hopper 63 provided at its bottom with a feed roll 64, and having a 40 hinged gate 65 for controlling the feeding of the material from the hopper 63 by the rotation of the feed wheel 64. The gate 65 has an operating rod 66 extending upwardly above the hopper 63, and is provided with a suitable wing nut 67 45 whereby it may be secured in adjusted positions. The feed wheel 64 delivers the material into a second hopper 68 which communicates with the housing 27, as shown. The hopper 68 is open at the rear end of the machine, as indicated at A in 50 Figure 1, and communicates with a suction chamber 69 having a suction trunk 71 connecting it with a settling chamber 72, provided with a suitable fan 73 for circulating air therethrough.

A partition 74 is provided in the settling chamber 72 between the suction trunk 71 and the intake to the fan 73, so that the fine dust-laden air drawn into the chamber 72 by the action of the fan 73, must pass downwardly around the lower edge of the partition 74, thereby causing 55 the heavier foreign matter drawn into the settling chamber to be precipitated into the bottom of said chamber, while only dust and such fine foreign particles as are held in suspension in the air are discharged from the outlet 75 of 60 the fan. A suitable gate or door 76 is provided at the bottom of the settling chamber whereby the contents thereof may be removed when necessary. The gate or door 76 may also be hinged in such a manner that when a predetermined 70 quantity of foreign matter is delivered into the settling chamber, the door will be automatically opened by the pressure of the material against the inner side thereof, whereupon the material will discharge from said chamber. 75

In the operation of the machine, the air drawn into the settling chamber by the fan 73 will enter the second hopper 68 through the opening A, and will pass around the lower portion of the feed wheel 64 and upwardly into the suction chamber 69, from whence it is drawn into the settling chamber through the trunk 71. The air thus drawn into the settling chamber by the fan 75, will remove from the unseparated material the very finest and lightest particles, such as pigeon seed, and other small seeds, and also dust and other foreign materials. The heaviest of these fine particles will be precipitated into the bottom of the settling chamber, while the dust will be discharged from the fan outlet 75 into a suitable receiving means, not shown.

From the foregoing, it will be understood that all the material delivered into the lower hopper 68 by the feed wheel 64 will be fed into the lower portion of the cylinder 8 at the rear of the machine and, due to the rotary movement of the cylinder, the material will travel towards the opposite end thereof, and the Durum wheat, rye, barley, and other material of certain length and weight, will lodge in the indentations 20 in the wall of the cylinder and will be carried upwardly and discharged into the trough-like member 48 at the forward end of the upper cylinder. It is also to be understood that the indentations in the wall of the cylinder will not only discriminate according to the length and size of the material being fed into it, but owing to the speed at which the cylinder revolves, a certain amount of centrifugal force is applied to the material or grain, causing the heaviest particles to find lodging in the indentations first. This will prevent the particles of lighter weight to find lodging in the indentations thus occupied, even though the length of such lighter material would permit them to lodge in the indentations.

All of the material received in the trough-like member 36 at the rear end of the cylinder 8, such as the small wheat, weed seeds, and other materials delivered thereto by the indentations 10 in the cylinder, will be delivered into the lower cylinder 9 through an opening 77 provided in the lower portion of the member 33 and into a chute 78 communicating with a hopper 79, connected with a feed opening 81 provided in an extension 82 of a head 83 suitably secured to the end of the cylinder 9, as best shown in Figure 1. The chute 78 may be formed from cast metal, and has an upstanding portion 80 to retain the material therein. It may be secured to the main frame as shown in Figure 3. An inspection door 90 may be provided in the chute 78 whereby an attendant may observe the flow of grain therethrough. Only the largest of the materials, such as the Durum wheat and other large wheat, and the coarse, rough material such as oats, barley, sticks, etc., will be removed from the material in the upper cylinder 8. It is to be particularly understood that the relative positions of the multiple trough-like members within the same cylinder, controls the amount of liftings and tailings in each section of the cylinder, said members being positioned so as to receive only certain materials of the desired length and weight, and irrespective of the sizes of the indentations opposite each trough-like member.

The extension 82 of the head 83 has a hub 84

secured thereto by suitable arms 85. A stub shaft 86, similar to the shaft 24 provided in the upper hopper 27, has one end secured in the hub 84 and has its opposite end rotatably mounted in a bearing 87 provided in the hopper 79. The hopper 79 and bearing 87 are supported upon the cross member 4 of the frame, as best shown in Figures 1 and 3. A suitable agitator 88 is secured to the stub shaft 86 and constantly agitates the material received in the hopper 79 to prevent it from clogging therein, when the machine is in operation. This agitator is similar to the agitator 50 provided in the housing 27 of the cylinder 8.

The inner portion of the hopper 79 is preferably cylindrical in configuration and is adapted to fit into the feed opening 81 of the extension 82 in such a manner as to provide a leak-proof joint between these members, it being understood that the extension 82 rotates synchronously with the cylinder 9.

The inner surface of the rear portion of the cylinder 9 is provided with suitable indentations 30, and the forward portion of this cylinder is provided with suitable indentations 40 which are smaller than the indentations 30. A pair of trough-like members 89 and 91 are mounted within the cylinder 9, and the bottoms of these members are inclined in the same direction as shown in Figure 1. The trough 89 has its forward portion secured to a plate member 92 fastened to a shaft 93 extending through the cylinder and having its rear end portion supported in the hub 84 of the head 83. The shaft 93 also extends through an aperture provided in the bottom of the trough 89 whereby the trough is firmly supported upon the shaft within the cylinder.

An inwardly extending flange 94 is provided within the cylinder 9 between the trough-like members 89 and 91, and provides a stop for the materials remaining in the bottom of the rear portion of the cylinder. In other words, the material such, for example, as the small Durum and large spring wheat which is not carried up by the indentations 30 and delivered into the trough-like member 89, will travel lengthwise through the rear section of the cylinder and be discharged therefrom through a plurality of openings 95 provided in the wall of the cylinder 9 adjacent to the flange 94. The material discharged through these openings will be received in a suitable member or hopper 96, preferably constructed of metal and secured to the longitudinally extending side rails 7-7 of the main frame, as shown in Figure 5. This hopper is disposed directly beneath the openings 95 in the cylinder 9 and may communicate with a suitable receiving means not shown.

All of the finer materials delivered into the trough-like member 89 by the indentations 30 in the cylinder 9 will be discharged into the forward section of the cylinder at the opposite side of the dividing flange 94, so that this material will be subjected to the action of the relatively smaller indentations 40 at that end of the cylinder.

All of the finest particles of the material delivered into the forward end portion of the cylinder 9 will be carried upwardly by the indentations 40 and delivered into the trough-like member 91, from whence it will be discharged from the machine through a spout 97 communicating with the discharge end of the trough 91. The spout 97 is provided on a plate 98 having a hub whereby it may be fixedly secured to a bushing 99. To the opposite end of the bushing 99 an arm 101 is secured, as shown at the right hand

side of Figure 1. The sleeve 99 is rotatably mounted in an end plate 102 similar to the plate 15 supporting the front end of the cylinder 8. The plate 102 may be secured to the uprights 5 3-3 of the main frame by suitable bolts, and has an opening 100 therein through which the spout 97 projects, as best shown in Figure 2.

When the machine is used for cleaning grain commercially, it may be desirable to retain a portion of the cracked and broken wheat with the cleaned grain, and this may readily be accomplished by proper adjustment of the trough-like member within the cylinders. The separation of the weed seeds from the small spring and broken wheat may also be varied by adjustment of the trough-like member 91, so that should it be desired to discharge the weed seeds and broken wheat as a single mixture, it may be readily accomplished by elevating the receiving edge of the trough 91 so that substantially all of the weed seeds will drop from the indentations 40 back into the cylinder, whereby they will be discharged from the cylinder, together with the broken wheat, through the spout 117. Conversely, should it be desired to mix only a portion of the broken wheat with the weed seeds, the receiving edge of the trough-like member 91 may be relatively lowered, whereby the smallest particles of the broken wheat will be lifted over the edge of the member 91 and be discharged from the machine together with the weed seeds, through the spout 42.

The forward end of the shaft 93 is rotatably supported in the sleeve 99, and has an arm 104 secured thereto which carries a screw 105 adapted to lockingly engage a link 106 which is pivotally mounted upon the end plate 102. The arm 104 has a slot 107 therein adapted to receive the link 106. In like manner the adjusting arm 101 has a slot 108 adapted to receive a link 109 to which the arm 101 may be secured by a suitable screw 111 for the purpose of locking the arm in adjusted position. A suitable collar 112 is secured to the shaft 93 and cooperates with the arm 101 to prevent longitudinal movement of the shaft 93. The front end of the cylinder 9 is provided with an annular member 113 provided with an outwardly extending portion 114 adapted to engage a pair of anti-friction rollers 115 and 116, secured 50 to the plate 102, and upon which the weight of the forward end of the cylinder is supported.

From the foregoing, it will be noted that the trough-like member 89 is mounted upon and secured to the shaft 93, to which the adjusting arm 104 is secured, so that by relatively moving the arm 104 with respect to the link 106, it will rotatably adjust the member 89 so as to cause the receiving edge thereof to be raised or lowered, whereby the desired separation of the material 55 may be obtained. The trough-like member 91 in the front end of the cylinder 9 is rotatably supported upon the shaft 93 and is secured to the plate 98 of the spout 97. Because of the plate 98 being secured to the sleeve 99, when the arm 101, which also is secured to the sleeve 99, is relatively moved, the trough-like member 91 will be 60 rotatably adjusted within the cylinder and independently of the trough 89, whereby the member 91 may be adjusted so as to pick up only the very finest particles, all of the other particles not being received in this trough, such for example the small spring wheat being discharged through the annular member 113 of the cylinder and into a spout 117, provided upon the end plate 102, as 65 clearly shown in Figures 1 and 2. The construc-

tion of the spout 117 is similar to that of the spout 59.

The means provided for operating the cylinders 8 and 9 is best shown in Figures 1, 2, and 3, and comprises a drive shaft 118, mounted in suitable bearings provided in the upper portion of the main frame, and having a suitable pulley 119 whereby it may be connected to a suitable source of power. A pinion 121 is secured to one end of the drive shaft 118 and meshes with a bevel gear 122, secured to one end of a shaft 123, to the opposite end of which a sprocket 124 is secured. This sprocket is adapted to drive a chain 125 operatively engaged with sprockets 126 and 127 suitably secured to the members 17 and 32 of the cylinders 8 and 9, respectively, as shown in Figures 1 and 3. The feed roll 64 is operatively connected with the shaft 123 by means of a pair of bevel gears 128 and 129, so that when the cylinders are operating, the feed roll will be rotated. The fan is shown provided with a pulley 131 adapted to be driven by a belt 132 from a pulley 133 secured to the opposite end of the drive shaft 118.

Another important feature of this invention resides in the provision of means for vertically adjusting one end of the machine so as to slightly tilt the cylinders with respect to the horizontal. Such a means is best shown in Figures 1, 4, and 5, and may consist of a pair of vertically movable feet or legs 134 and 135, slidably mounted in suitable guides provided in the lower cross rail 6 of the main frame. The foot 134 is here shown having its upper end pivotally connected to one end of a lever 136 pivoted at 137 to a cross member 138, secured to the upright legs 3-3 of the main frame. The foot 135 has its upper end pivotally connected to an arm 139 pivoted at 141 to the cross member 138. The opposite end of the arm 139 is shown carrying a pin 142 received in a slot 143 provided in the lever 136. The lever 136 is provided with a hand grip 144 and has a projection or rib 145 thereon adapted to selectively engage the teeth of a suitable quadrant 146, secured to one of the upright legs of the main frame. The pivotal connection of the lever 136 with the cross member 138 is such that the swinging end of the lever is frictionally held in engagement with the quadrant 146, whereby the lever will remain in its adjusted positions.

When the lever 136 is swung upwardly, when viewed as shown in Figure 5, the feet 134 and 135 will be moved downwardly thereby causing the machine frame to be elevated, with the result that the forward ends of the cylinders will be correspondingly elevated and thereby retard the movement of the material through the machine. Conversely, when the lever is moved downwardly from the position shown in Figure 4, the machine frame will be lowered from the position shown in Figure 4, thereby lowering the front ends of the cylinders with the result that the material will travel faster through the machine. Thus by means of the lever 136, the flow of the material through the cylinder may be controlled at will.

In the operation of this novel grain separator, the material to be separated and cleaned is delivered into the hopper 63 at the upper rear portion of the machine. The gate 65 is then opened by manipulation of the rod 66 to control the feeding of the material into the receiving end of the upper cylinder 8. As the material is discharged from the hopper 63 into the lower hopper 68, the flow of air through this hopper beneath

the feed roll 64 will remove from the material all of the finest particles, such as dust, pigeon seed and other such materials. These lighter materials will be drawn into the settling chamber 72, where the heaviest of these lighter particles will be precipitated into the bottom of the chamber, while the dust and such particles as are held in suspension in the air current, will be drawn upwardly into the fan 73 and discharged therefrom through the outlet 75 thereof.

The remaining materials will be delivered into the receiving end of the upper cylinder 8, as shown in Figure 12, and will be subjected to the action of the indentations 10 in the rear section of this cylinder and will be constantly agitated, and the smaller particles, such as medium sized wheat, small Durum and small spring wheat, will be removed from the mass by the indentations 10 and delivered into the trough-like member 36 of the cylinder 8. The larger materials, such as Durum and other large wheat kernels, and also the coarse, rough material such as oats, barley, sticks, straw, and the like, which is not carried up by the indentations 10, will pass outwardly toward the opposite end of the cylinder 8, where they will come into contact with the relatively larger indentations 20, provided at that end of the cylinder. All of the material delivered into the trough-like member 36 will be discharged into the chute 78 from whence it is delivered into the hopper 79 and fed into the receiving end of the lower cylinder 9. The degree of separation between the large wheat and the smaller particles is controlled by relatively adjusting the receiving edge of the trough-like member 36 so as to cause only certain materials to be delivered into this trough.

The material delivered into the forward section of the cylinder 8 will be subjected to the action of the relatively large indentations 20 which are of such size as to pick up the large Durum wheat, rye, and barley and carry them upwardly and discharge them into the trough-like member 48, as shown in Figure 11. The coarse, rough material, such as the oats, long, poorly threshed barley, small sticks and straw will be crowded out of the indentations 20 by the relatively heavier wheat kernels, and will therefore drop out of the indentations and fall back into the cylinder, or into the relatively smaller auxiliary trough 54 provided upon the member 48, whereby they will be returned to the intermediate portion of the cylinder for further separation. The receiving edge of the member 48 is positioned at such an elevation as to cause only the large, clean wheat to be thrown thereon into the member 48, from whence it is discharged through the chute 42 into a suitable receiving means. The delivery of the large wheat kernels into the member 48 is controlled largely by the relative position of the receiving edge of this member, which will be understood by reference to Figures 9, 10, and 11. The cylinder 8 is also operated at a speed whereby the centrifugal force acting on the particles and tending to hold them in the indentations, will be overcome by gravity, when the various materials reach certain elevations, thereby making it possible, by properly adjusting the receiving edge of the trough-like member 48, to cause only the large, clean wheat to be delivered thereinto.

In some instances when the proportion of large wheat in the mixture delivered into the forward portion of the cylinder 8, is small, all of the wheat may be separated or removed from the oats and other rough material by the inden-

tations 20 before any of the wheat reaches a position in the cylinder beneath the pivoted members 57. When this occurs some of the rough material such as oats, and barley, may lodge in the indentations 20 and be carried upwardly thereby and thrown over the receiving edge of the member 48, in which case it would be discharged from the spout 42 with the clean large wheat. To prevent such an occurrence the receiving edge of the member 48 is preferably inclined as shown in Figure 1 so that said edge is higher at the forward end of the cylinder where the oat kernels are more apt to be carried up by the indentations. By thus making this edge higher at the forward end of the cylinder, the danger of oats and barley being carried over the edge is minimized.

To further guard against this occurrence, however, the hinged members 57 are provided at the forward end of the trough-like member 48, which members may be positioned as shown in Figure 9, whereby all the coarse material discharged into the member 48 at the end of the cylinder will be received by the members 57 and will be conveyed across the member 48 and discharged into the auxiliary trough 55, whereby it will be returned to the intermediate portion of the cylinder for further separation. It will thus be seen that by the provision of the members 57 and the independent adjustment of the trough-like members 36 and 48, an accurate and complete separation of the large wheat may be made from the relatively smaller particles in the mass, and, in like manner, all of the coarse, rough materials, such as oats, barley, sticks, straws and the like, is also removed therefrom in the first cylinder.

The remaining unseparated smaller materials, as hereinbefore stated, are delivered into the receiving end of the lower cylinder 9, and as they pass through the rear portion thereof all of the medium sized wheat, small Durum and large spring wheat is removed from the mass and discharged through the openings 95 in the intermediate section of the cylinder, into the discharge spout or hopper 96. The relatively finer particles, such as the small spring wheat and weed seeds are received in the trough-like member 89, from whence they are delivered into the forward section of the cylinder 9. As they pass through this section all of the weed seeds and other fine particles will be removed from the remaining particles by the action of the relatively smaller indentations 40 and will be delivered into the member 91 to be discharged from the spout 97, provided at the forward end of the machine. The remaining particles, which will consist mostly of small spring wheat and broken kernels of wheat, will be discharged through the spout 117 of the cylinder 9.

The amount of material delivered into the cylinder 9 from the upper cylinder 8 is controlled by adjustment of the trough-like member 36 at the rear end of the upper cylinder.

The trough-like members 89 and 91 are adapted for independent rotary adjustment by manipulation of the adjusting levers 104 and 101, respectively, whereby an accurate separation of these particles may be obtained. Also by vertically adjusting the front end of the machine to change the positions of the cylinder with respect to the horizontal, the material feeding through the cylinder may be controlled as desired, and this adjustment in conjunction with the independent adjustments of the trough-like members 36, 48, 89 and 91, provides means whereby a very thorough and complete separa-

tion of all particles contained in the mass may be obtained.

From the foregoing it will be noted that seven separations are made, which are as follows: (1) the dust and very finest particles are discharged from the outlet 75 of the fan; (2) the relatively heavier particles of the material removed by the air current passing through the suction chamber 69 is delivered into the bottom of the settling chamber 72; (3) the clean Durum and other large wheat is discharged from the spout 42; (4) the oats, barley, sticks, straws and other rough material is discharged from the spout 59; (5) the small Durum, medium sized wheat, and large spring wheat is discharged from the hopper or spout 96; (6) the small spring wheat and similar sized particles are discharged from the spout 117; and (7) the weed seeds and other fine particles are discharged from the spout 97. By relatively adjusting the trough-like members 36 and 48 within the cylinder 8, the machine may be so adjusted as to cause it to not only make a very thorough and complete separation of the Durum wheat, barley and rye, from the oats and remaining materials, but also a separation of spring and other small wheat may be made from the best grades of Durum. The members 89 and 91 in the lower cylinder 9 may be so adjusted as to cause more or less of the material which ordinarily would discharge from the opening 95 in the cylinder 9 to be carried into the other section of this cylinder, whereby they would be discharged from the spout 117 and mixed with the small spring wheat discharging from this spout. Also by relatively adjusting the position of the member 91 it may be so set as to cause it to pick up only the very finest of the weed seeds, whereby the relatively larger weed seeds will be discharged from the machine through the spout 117, together with the other materials discharging therefrom.

Figure 11 is an enlarged detail sectional view illustrating a wall section of the forward portion of the cylinder 8, showing how the large wheat kernels are carried upwardly by the indentations 20 and delivered into the member 48 over the upper edge thereof, while the oats and other large tailings are discharged by gravity from the indentations of the cylinder wall before they reach the upper edge of the member 48. It will be noted by referring to this figure that centrifugal force, controlled by the peripheral speed of the cylinder, operates against gravity to retain the different materials in the pockets until they reach certain heights. Thus by operating the cylinders at the proper speed and positioning the receiving edge of the trough-like member 48 at the proper elevation, only the large heavy wheat kernels will be delivered into the member 48.

In the drawings, we have shown the trough-like member 48 as being the only member having its receiving edge arranged at an incline with respect to the horizontal, but it is to be understood that one or more of the other members 36, 89 and 91 may also have their receiving edges similarly disposed, if desired, without departing from the scope of the invention.

The machine as disclosed in the drawings, particularly Figure 1, embodies two cylinders and is adapted for making several separations as hereinbefore stated, and thus provides a machine of the class described which is capable of handling and separating from one another, various kinds of grains and small seeds and delivering them to

separate receiving means. It is also capable of grading such grains as, for example, wheat, because by proper adjustment of the trough-like members 36—48, 89 and 91, the clean wheat may be classified or graded into three separate grades, namely, the small wheat, the medium sized wheat, and the large wheat. By adjustably mounting the trough-like members as disclosed, they may be relatively adjusted independently of each other whereby the machine is rendered very flexible, so that almost any desired degree of separation and classification may be obtained.

For certain classes of work, when fewer separations are required as, for example, separating from one another, weed seeds, wheat and oats, we have found that the lower cylinder 9 may be dispensed with, in which case the machine is constructed with the upper cylinder 8 only. In such a machine, it may also be possible to secure the trough-like members 36 and 48 in fixed relation, when once their proper positions have been located within the cylinder, whereby a very simple and inexpensive machine may be provided.

We claim as our invention:

1. A separator comprising a cylinder mounted for rotary movement and having its wall surfaces provided with groups of different sized indentations, means for feeding material to said cylinder, a plurality of inclined trough-like members mounted within said cylinder and each aligned with a group of said indentations, and each member being adapted to receive certain materials carried upwardly by the indentations aligned therewith, means for independently raising or lowering the receiving edges of said members whereby each may be positioned to cause only certain materials to be received therein, and means mounted within one of said members adapted to be positioned to receive elective portions of the material delivered thereto and convey it over said member into a return trough positioned at the opposite side thereof, whereby said elective portions of the material will be returned to the cylinder for further separation.

2. A separator comprising a rotatable cylinder having groups of different sized indentations in the walls thereof, trough-like members within said cylinder having their bottoms inclined in opposite directions from an intermediate point in the cylinder and each aligned with a group of said indentations, each of said members having a receiving edge positioned adjacent to the wall of the cylinder and over which certain of the materials are lifted by the indentations in the cylinder walls and delivered into said members, means for independently raising or lowering the receiving edges of said trough-like members whereby they may be positioned to cause only certain materials to be received therein, means pivotally mounted within one of said trough-like members and having its receiving edge adapted to be positioned adjacent the receiving edge of said member to receive elective portions of the material delivered thereto and convey it over said member to be returned to the cylinder for further separation, and means by which said pivoted means may be moved into inoperative position.

3. A separator comprising a rotatable cylinder having suitable indentations in the walls thereof, trough-like members within said cylinder having their bottoms inclined in opposite directions from an intermediate point in the cylinder, each of said members having a receiving edge positioned adjacent to the wall of the cylinder

and over which certain of the materials are lifted by the indentations in the cylinder and delivered into said members, means for independently raising or lowering the receiving edges 5 of said trough-like members, whereby they may be positioned to cause only certain materials to be lifted thereover, the receiving edge of one of said trough-like members being inclined, whereby it is higher at one end than at the other, to thereby prevent certain of the coarser materials 10 from being lifted thereover into said member, an auxiliary return trough secured to the side of said member opposite from said inclined edge, and means for conveying certain of the material 15 delivered to said member into said auxiliary trough, whereby it is returned to the cylinder for further separation.

4. A separator comprising a plurality of rotatable cylinders, arranged one over another, and 20 having their walls provided with groups of different sized indentations, a plurality of trough-like members arranged within said cylinders and each having an edge positioned adjacent to a cylinder wall and over which certain materials 25 are lifted by the indentations in the cylinder walls, means for independently adjusting said trough-like members to raise or lower the receiving edges thereof whereby a complete separation 30 of the materials may be obtained, and means for feeding the mass of material into one end of one of said cylinders, comprising a hopper having its discharge connected to the intake 35 of the cylinder, and having means for drawing a current of air through the material feeding from the hopper to the cylinder whereby dust and 40 foreign lighter particles are removed from the mass of material before the latter is delivered into the receiving cylinder.

5. A separator comprising an upper cylinder 40 having suitable indentations in the inner wall surface thereof, trough-like members arranged in said cylinder and inclined in opposite directions, a cylinder disposed beneath said upper cylinder, one of said trough-like members being 45 adapted to receive certain materials carried upwardly by the indentations at one end of the upper cylinder and deliver them into the lower cylinder for further separation, and the other of said trough-like members being adapted to 50 receive certain of said materials and discharge them from one end of the upper cylinder as a finished product, the remaining materials not delivered into said second mentioned member being 55 discharged from the end of the cylinder, means for independently adjusting the trough-like members in said cylinders, whereby the receiving edges thereof may be positioned to cause only certain materials to be lifted thereover, and means for feeding the material to be separated 60 into said upper cylinder, comprising a feed regulating means and a suction means for removing dust and other foreign lighter material from the mass before it is delivered into the cylinder.

6. A separator comprising an upper cylinder 65 having suitable indentations in the inner wall surface thereof, trough-like members arranged in said cylinder and inclined in opposite directions, a cylinder disposed beneath said upper cylinder, one of said trough-like members being 70 adapted to receive certain materials carried upwardly by the indentations at one end of the upper cylinder and deliver them into the lower cylinder for further separation, and the other of said trough-like members being adapted to 75 receive certain of said materials and discharge

them from one end of the upper cylinder as a finished product, said second mentioned trough-like member having its receiving edge inclined upwardly in the direction of travel of the material to prevent elective portions of the larger material from lifting over a portion of said edge, the remaining materials not delivered into said second mentioned member being discharged from the end of the cylinder as tailings, means for independently adjusting the trough-like members in said cylinders, whereby the receiving edges thereof may be positioned to cause only certain materials to be lifted thereover, and means for feeding the material to be separated into said upper cylinder, comprising a suction device for removing dust and other foreign lighter material 10 from the mass before it is delivered into the cylinder. 15

7. A separator comprising a rotatable cylinder 20 having suitable indentations in its walls adapted to convey different materials, a plurality of trough-like members adjustably mounted within the cylinder and adapted to receive selective materials from said indentations and convey them to separate receiving means, means for feeding the material to be separated into one end of the cylinder, auxiliary return troughs secured to the 25 opposite sides of one of said trough-like members, one of said auxiliary troughs being positioned to receive selective material from certain of the indentations in the walls of the cylinder and return said material for further separation, conveying means mounted within the trough-like member to which said return troughs are 30 secured adapted to receive and convey certain materials delivered over the receiving edge of said trough-like member, into the return trough at the opposite side thereof, and means whereby 35 said conveying means may be moved to an inoperative position. 40

8. A separator comprising a rotatable cylinder having suitable indentations in its walls adapted to convey different materials, a plurality of trough-like members adjustably mounted within the cylinder and adapted to receive selective materials from said indentations and convey them to separate receiving means, means for feeding the material to be separated into one end of the cylinder, auxiliary return troughs secured to the 45 opposite sides of one of said trough-like members, one of said auxiliary troughs being positioned to receive selective material from certain of the indentations in the walls of the cylinder and return said material for further separation, and a plurality of material conveying elements 50 mounted within the trough-like member to which said return troughs are secured, adapted to receive and convey certain materials delivered over the receiving edge of said trough-like member, into the return trough at the opposite side thereof, said conveying elements being independently movable to control the diverting of 55 said certain materials over said trough-like member. 60

9. A separator comprising a rotatable cylinder having suitable indentations in its walls adapted to convey different materials, a plurality of inclined troughs within the cylinder adapted to receive selective materials from said indentations 70 and convey them from the cylinder, and means for feeding the material to be separated to said cylinder comprising a hopper having its discharge connected with the intake of the cylinder, means in the bottom of the hopper for regulating the 75

flow of material therefrom, a settling chamber, a trunk connecting said chamber with the discharge of the hopper, and a suction device connected with said chamber for drawing air through said trunk into the chamber, whereby dust and other foreign lighter matter contained in the material being fed to the cylinder is removed therefrom before it reaches the cylinder.

10. A separator comprising a rotatable cylinder having suitable indentations in the walls thereof adapted to convey different materials, a plurality of inclined troughs within the cylinder adapted to receive selective materials from said indentations and convey them from the cylinder, the material remaining in the cylinder being discharged directly therefrom, and means for feeding the material to be separated to said cylinder comprising a hopper having its discharge connected with the intake of the cylinder, means in the bottom of the hopper for regulating the flow of material therefrom, said hopper having a transverse air passage beneath its discharge through which the material discharging therefrom passes, a settling chamber, means establishing communication between said chamber and the air passage beneath the hopper, and a suction device connected with said chamber whereby air is drawn through said transverse air passage and into the settling chamber to thereby remove dust and other foreign lighter matter from the material being fed to the cylinder.

11. A separator comprising a rotatable cylinder having suitable indentations in the walls thereof adapted to convey different materials, a plurality of inclined troughs within the cylinder adapted to receive selective materials from said indentations and convey them from the cylinder, a hopper arranged at one end of the cylinder and having means at its discharge for controlling the delivery of material to the cylinder, a suction chamber arranged adjacent to said hopper and having its intake disposed adjacent to the discharge of the hopper, and a suction device connected to said suction chamber whereby a current of air is drawn through the flow of material discharging from said hopper, whereby dust and other lighter foreign matter contained in the material is re-

moved therefrom before the material is delivered into the cylinder.

12. A separator comprising a rotatable cylinder having suitable indentations in the walls thereof adapted to convey different materials, a plurality of inclined troughs within the cylinder adapted to receive selective materials from said indentations and convey them from the cylinder, a hopper arranged at one end of the cylinder and having means at its discharge for controlling the delivery of material to the cylinder, a suction chamber arranged adjacent to said hopper and having its intake disposed adjacent to the discharge of the hopper, a settling chamber connected to said suction chamber, a suction device connected to said settling chamber, whereby a current of air is drawn through the suction chamber and into the settling chamber, whereby dust and other lighter foreign matter contained in the material is removed therefrom and delivered into the settling chamber, before the material is fed into the cylinder, and means whereby the heavier particles delivered into the settling chamber are retained therein while the dust is removed therefrom by said suction device.

13. A separator comprising a rotatable cylinder having means therein adapted to receive and convey different selective materials, a plurality of inclined troughs within the cylinder adapted to receive selective materials from the means in said cylinder and convey them to separate receiving means, an auxiliary hopper connected to one end of the cylinder, a main hopper over said auxiliary hopper and having means at its discharge for regulating the flow of material therefrom into the auxiliary hopper, a suction chamber above the auxiliary hopper and connected thereto, said auxiliary hopper having an air intake, and a suction device connected to said suction chamber, whereby air is drawn through said auxiliary hopper and through the flow of material passing therethrough from the main hopper, whereby dust and other foreign lighter matter is removed from the material before it is delivered into the cylinder.
